UNITED STATES PATENT OFFICE

152,264

DESIGN FOR A RANGE

Michael Hallward, Swampscott, Mass., assignor
to Glenwood Range Company, Taunton, Mass.,
a corporation of Massachusetts

Application April 2, 1947, Serial No. 138,106

Term of patent 3½ years

(Cl. D81—4)

To all whom it may concern:

Be it known that I, Michael Hallward, a British subject and resident of Swampscott, in the county of Essex, State of Massachusetts, have invented a new, original, and ornamental Design for Ranges, of which the following is a specification, reference being had to the accompanying drawing, forming part thereof.

Fig. 1 is a front elevation of a range, showing my new design, and

Fig. 2 is a side elevation thereof.

The side of the range, not shown, is substantially like the side shown. The top is substantially plain and has four burner covers, as shown.

I claim:

The ornamental design for a range, as shown and described.

MICHAEL HALLWARD.
